UNITED STATES PATENT OFFICE.

JOHN B. LARDINOIS, OF BRUSSELS, WISCONSIN, ASSIGNOR OF ONE-HALF
TO GABRIEL PIERRE, OF BRUSSELS, WISCONSIN.

SAFETY-GATE FOR DRAWBRIDGES.

No. 809,817.

Specification of Letters Patent.

Patented Jan. 9, 1906

Application filed September 1, 1905. Serial No. 276,748.

To all whom it may concern:

Be it known that I, JOHN B. LARDINOIS, a citizen of the United States, residing at Brussels, in the county of Door and State of Wisconsin, have invented a new and useful Safety-Gate for Drawbridges, of which the following is a specification.

This invention relates to safety-gates for drawbridges, and has for its object to provide a device of the class embodying new and improved features of simplicity, efficiency, and durability.

A further object of the invention is to provide a device of the class embodying a vertically-slidable gate disposed at the end of the abutment to the draw and having weighted levers supported upon struts pivoted beneath the approach and capable of raising the gate and closed and held normally closed by a cam carried by the bridge.

With these and other objects in view the present invention consists in the combination and arrangement of parts, as will be herein-after fully described, shown in the accompanying drawings, and particularly pointed out in the appended claims, it being understood that changes in the form, proportion, size, and minor details may be made without departing from the spirit or sacrificing any of the advantages of this invention.

In the drawings, Figure 1 is a perspective view of a conventional drawbridge with the improved gate applied. Fig. 2 is a transverse sectional view with the bridge closed. Fig. 3 is an end view of one of the abutments with the bridge open. Fig. 4 is a view in side elevation of a bridge-abutment with the improved gate mounted thereon with a modified form of actuating mechanism.

Like characters of reference indicate corresponding parts in all of the figures of the drawings.

The safety-gate forming the subject-matter of this application is adapted for use upon a swinging bridge of the ordinary construction having a draw-span 10, swinging upon a central pier 11 and communicating with the approaches 12 and 13, supported on any approved form of abutments, as 14 and 15. Adjacent the end of the approach registering with the draw-span is formed a transverse groove 16, communicating with openings 17 through the flooring of the approach. Within the groove is disposed a bar 18, having its

opposite ends 19 bent at right angles and depending through the openings 17. Transversely beneath the approach is disposed the beam 20, secured to the ends 19 of the bar 18 and together therewith forming the vertically-slidable gate. The beam 20 slides along a vertical guide 21, and to hold the gate at its upward limit levers 22 are provided, pivotally secured at one end to the beam, as by staples 23, and at the other end carrying weights 24. At 25, a point intermediate their ends, the levers 22 are pivoted upon the upper ends of struts 26, which are in turn pivoted, as at 27, to the abutment and their movements limited by the pins 28. Centrally of the beam 20 is mounted a roller 29, and upon the ends of the swing-span are mounted depending curved cams 30, proportioned and disposed to engage and depress the roller 29.

To raise the gate, springs 31 may be substituted for the weights, as shown in Fig. 4, and may be of any approved form and attached to the abutment in any approved manner.

With the parts assembled as shown in Fig. 1, the gate is wholly out of the way and offers no obstruction to travel or any other use of the bridge. When, however, the draw is opened, the cam 30 rides off from the roller 29, which leaves the gate free to be raised by the weight 24. When the draw is closed, the cams 30 engage the rollers and depress the gate again to the position shown in Figs. 1 and 2.

Having thus described the invention, what is claimed is—

1. The combination with a drawbridge of an abutment, a gate vertically slidable adjacent the end of the abutment, a strut pivotally connected at its lower end to the abutment, a lever pivoted upon the upper end of the strut and with one end pivotally connected with the gate, a weight carried on the end of the lever opposite the gate, a roller mounted on the gate and a cam carried by the bridge disposed to engage and depress the roller. 100

2. The combination with a drawbridge of an abutment, a beam mounted transversely and movable vertically of the abutment, a gate carried by the beam, a strut pivoted at its lower end to the abutment, a lever fulcrumed upon the strut and at one end to the beam, a weight carried by the lever at the end opposite the beam, a roller mounted

upon the beam and a cam carried by the bridge-span disposed to engage and depress the roller.

3. The combination with a drawbridge of
5 an abutment, a guide secured to the abutment, a beam slidably mounted and vertically movable upon the guide and disposed transversely of the bridge, a gate carried upon the beam, a strut pivoted at its lower
10 end to the abutment, a lever fulcrumed upon the strut and with one end pivoted to the

beam, a weight carried by the lever at the end opposite the beam, a roller mounted upon the beam and a cam carried by the bridge to engage and depress the roller.

In testimony that I claim the foregoing as my own I have hereto affixed my signature in the presence of two witnesses.

JOHN B. LARDINOIS.
